PRODUCTION OF LOW COLD-TEST OILS BY UREA DEWAXING**Gordon D. Kerns, Hammond, Ind., assignor to Standard Oil Company, Chicago, Ill., a corporation of Indiana****Application March 8, 1957, Serial No. 644,761****3 Claims. (Cl. 208—25)**

This invention relates to improvements in the dewaxing of hydrocarbon oils. More particularly, it relates to an improved continuous process for the preparation of low cold-test oils from wax-containing petroleum stocks.

The ability of urea to form under suitable conditions solid crystalline complexes, commonly called adducts, with certain straight chain organic compounds is well known. Numerous applications of this property have been proposed, including the dewaxing of wax-containing petroleum stocks in order to obtain products having low pour points. Although these proposed methods for dewaxing petroleum stocks by means of urea are suitable for small-scale operations, their use on a commercial scale presents operating difficulties and disadvantages which render them unattractive. Thus, for example, it has been proposed to carry out the dewaxing operation batchwise in a reaction vessel equipped with a filter in the bottom thereof, by means of which the dewaxed oil is separated from the solid adduct; in addition to foregoing the operating efficiencies and advantages attending the use of a continuous process, such a method when applied commercially requires unreasonably long filtration times because of the thick filter cake which is produced. Other proposed methods contact the waxy oil with solutions of urea; thus two liquid phases are present in the reactor, giving rise to operating difficulties occasioned by the formation of emulsions which are often difficult to break. Still other methods which contemplate the use of solid urea involve costly and difficult methods of operation such as the use of screw conveyors for transporting solid materials.

An object of the present invention is to provide improved methods and means for the dewaxing of petroleum stocks. Another object is to provide an improved continuous process for the production of low cold-test oils on an industrial scale with minimum investment and operating costs while avoiding hitherto encountered operational difficulties. Other objects and advantages of this invention will be apparent to those skilled in the art from the following description.

In accordance with the method of this invention, low cold-test oils having pour points within the range of about -10° to -70° F. are produced by contacting a wax-containing hydrocarbon oil having a viscosity within the range of about 40 to 300 SSU at 100° F. and a pour point of about 0° to 100° F. with finely divided solid urea in an amount of about 3 to 8, and preferably from about 4 to 6, pounds per pound of wax in the oil, about 0.5% to about 10% by volume, based on the waxy oil, of methanol, and about 0.1 to about 3 volumes of an inert hydrocarbon diluent liquid, at least a portion of which is used as a slurring agent for regenerated and recycled solid urea. The contacting is continued at a temperature of about 40° to about 120° F., and preferably from about 60° to 100° F., for a time sufficient to effect ad-

2

duct formation, normally about 0.1 to 1.5 hours, after which the adduct and any unreacted urea is separated from the diluent oil by means of filtration, centrifugation, or the like. The filtrate, consisting of diluent and dewaxed oil containing a portion of the methanol supplied to the contacting step, is stripped of methanol and diluent, which are recovered for reuse, yielding the desired low cold-test product. The adduct cake is repulped to form a slurry with recycled wax-containing diluent liquid from a subsequent washing zone, and the slurry is heated to a temperature above about 180° F. but below the melting point of urea and is pumped to a decomposing zone. In the decomposing zone the adduct decomposes, liberating solid particles of regenerated urea and the adducted wax which goes into solution in the diluent liquid. The methanol present flashes off as a vapor and is condensed and recovered for reuse. The particles of regenerated solid urea settle to the bottom of the decomposing zone, leaving a supernatant solution of liberated wax in diluent liquid, which is removed continuously and stripped to recover the diluent for reuse. The regenerated solid urea is collected at the bottom of the decomposing zone and is pumped as a slurry to the first of two washing zones where recycled diluent is added as a wash liquid. The solid urea is separated from the wash liquid by continuous decantation and is pumped as a slurry to the second washing zone where the washing operation is repeated. From the second washing zone urea slurry is recycled to contact fresh charging stock. The wash liquid is used to slurry the adduct cake, as described above.

The process of my invention provides an improved method whereby oils having extremely low pour points can be prepared. These products are useful as transformer oils, automatic transmission fluids, refrigerator oils and the like, which have heretofore been prepared from certain low-wax crudes, such as Kittrell and Winkler. Owing to the decreasing supply of low-wax crudes, however, it has become necessary to devise another technique for producing low cold-test oils which can be used on an industrial scale. This is supplied by the method of my invention, which is a unitary continuous process providing the utmost in simplicity of operation, minimum investment cost, and most efficient utilization of all process materials, leading to minimum operating cost.

In producing the desired low cold-test oils there is used as the charging stock a petroleum fraction having a viscosity of about 40 to 300 SSU at 100° F. and a pour point within the range from about 0° F. to about 100° F., suitably a Mid-Continent fraction. These viscosities correspond in general to the SAE 10, SAE 5, and lighter grades. The minimum pour point attainable appears to depend on the viscosity of the oil, varying directly as a logarithmic function thereof. Previous solvent dewaxing, in some cases, also affects the pour point obtained by urea-dewaxing according to my technique. Oils having viscosities of 40 to 150 SSU at 100° F. are urea-dewaxed to the same low pour point whether previously dewaxed or not. In the viscosity range of 150-200 SSU, urea-dewaxing produces oils of low pour point only from oils which have been previously dewaxed by conventional means to a pour point of about 0° to 10° F. From 200 to 300 SSU, urea forms adducts with the waxes in both undewaxed distillates, and cold-pressed oils, but the improvements in pour point are not as great as in the case of lower viscosity oils. In all cases, however, it is preferred that the charging stock be previously dewaxed to a pour point of about 0° F. to 10° F. by any convenient means such as propane dewaxing, cold-pressing, or the like. This is desirable in order to minimize

the quantities of solid materials which must be handled in the urea dewaxing operation.

To the waxy charging stock there is added a slurry of finely divided particles of urea in an inert hydrocarbon diluent, which slurry is recycled from a subsequent urea regeneration zone to be described in more detail hereafter. In order to insure substantially complete removal of adductable waxy materials in the charging stock, it is necessary that at least about 3 pounds of urea per pound of adductable material in the charging stock be supplied. In practice this may range from about 3 to 8 pounds of urea per pound of wax, and preferably from about 4 to 6. The presence of solid materials in such quantities and the fact the urea-wax adducts tend to be sticky and pasty in nature makes it desirable that the charging stock be diluted with a hydrocarbon diluent which is a further quantity of the liquid used to form the slurry of urea. The diluent, which is advantageously employed in proportions up to 300% or more based on the charging stock, thins the mixture, insuring better contact between the urea and oil, and facilities separation of solid materials from dewaxed oil, as by filtration. The quantity of diluent to be used will depend on the viscosity of the charging stock, the wax content thereof, and the efficiency of the mixing and separating equipment. It is, of course, desirable to use diluents in as low a concentration as possible in order to minimize the difficulty and expense of recovery thereof. I prefer to use between about 50 and 150% by volume thereof, based on the charging stock. The diluent may be any hydrocarbon liquid which is unreactive with urea under the conditions employed and which has a boiling point sufficiently removed from that of the product oil to permit a clean separation therefrom by distillation. Among the diluents which can be used, although not necessarily with equivalent results, are naphthas and other hydrocarbons, including pentane, isopentane, isoctane, benzene, toluene, light alkylate, and the like. A particularly suitable diluent is a light alkylate obtained by alkylation of a mixed butylene stream with isobutane and subsequent fractionation to remove high boiling material. Light alkylate is inert to urea at all temperatures and has a boiling range of about 120° to 350° F., permitting it to be readily stripped from the dewaxed oil, leaving a treated material free from extraneous substances.

To the mixture of diluted oil and solid urea, there is added an activator which is required for adduct formation within a reasonable time. Suitable activators include oxygenated solvents for urea, such as water and the lower alcohols, among which methanol is particularly preferred. When methanol is used, it is added in an amount of about 0.5% to about 10%, and preferably about 3%, by volume based on the waxy oil, a quantity which in the absence of any other liquid is sufficient merely to moisten the surface of the urea particles without the appearance of any substantial liquid phase. In some cases it may be desirable to use a minor amount of water in conjunction with the methanol. In such cases between about 2 and 10% by volume based on the methanol may be added.

The mixture of charging stock, diluent, urea and activator is transferred to a reactor wherein adduction between urea and the waxy materials in the oil takes place. The reactor is suitably a vertically elongated vessel containing one or more "doughnut" baffles which serve to divide the reactor into two or more mixing stages, each of which is supplied with means for stirring the reaction mixture. The reactor should be sized such that the average residence time within the vessel is within the range between about 0.1 and 1.5 hours or more, and preferably about one hour. Adduction occurs at any temperature below about 130° F., with the range from about 60° to 100° F. being preferred. Temperatures above about 100° F. are less satisfactory because of increasing instability of the adduct, and temperatures below about

60° F. are less satisfactory because of contacting and filtering difficulties arising from increased viscosity of the reaction mixture. Since the adduction reaction is exothermic, it will be found convenient to cool the mixture entering the reactor to a temperature about 5-10° F. below the maximum temperature desired in the reactor. In this way the liberated heat of reaction is absorbed by the reactants, and no external cooling means need be used. Otherwise, some means for controlling the maximum temperature in the reactor must be provided.

From the reactor the slurry of adduct, unreacted urea, dewaxed oil and methanol is conveyed to a separation zone for removal of the solid materials from the diluted dewaxed oil. The separation zone is preferably a conventional drum-type filter, although other means such as a centrifuge can be used. When a drum filter is used, it is advantageous to carry on the filtration with an inert gas such as nitrogen under superatmospheric pressure within the case of the filter. The use of inert gas pressure at this point has an important advantage in addition to increasing the speed of filtration. The inert gas which leaves the filter along with the filtrate is subsequently recovered, recompressed, and recycled to the filter case. In this way it soon becomes saturated with methanol vapor and its presence within the filter serves to repress the further evaporation of methanol from the adduct-oil mixture. The filtrate present at this stage is saturated with methanol and urea. Evaporation of methanol from this filtrate tends to precipitate solid urea within the pores of the filter cloth. By inhibiting the evaporation of methanol, blinding of the filter cloth with urea particles is discouraged.

The filtrate, consisting of low-pour oil, diluent, and a portion of the methanol activator, is sent to a vessel wherein the inert gas is separated, recompressed, and recycled to the filter. The diluted oil is then stripped of methanol and diluent, which are recovered and recycled. The stripped product thereby obtained is the desired low cold-test oil.

The adduct cake from the filter is washed with recycled diluent liquid to remove occluded oil and is then reslurried with a recycled stream of diluent which has been used to wash the regenerated urea in a subsequent zone to be more fully described below. Sufficient diluent liquid is supplied to form a slurry which is easily pumped by conventional slurry pumps, suitably having a solids content within the range from about 20 to 60 weight percent, and preferably about 30%. The slurry is heated to a temperature within the range above about 180° F. but below the melting point of urea and preferably between about 200 and 240° F. and is passed to a vessel wherein vapors of methanol and a portion of the diluent flash overhead, are condensed, separated and recycled. When the adduct decomposes, the liberated wax goes into solution in the diluent liquid and the urea is regenerated as finely divided particles which settle to the bottom of the decomposer, where they are collected as a slurry containing about 20 to 75% solids, and preferably about 60%, which is pumped to the first of two washing stages wherein the regenerated urea is washed of occluded wax and oil. A solid-free solution of liberated wax in diluent liquid is withdrawn from a point near the top of the decomposer and is flashed and stripped to separate diluent which is recycled and wax which may be further processed as desired, or used as a charging stock to a catalytic cracking operation.

The slurry of regenerated urea leaving the decomposer contains significant quantities of wax dissolved in the diluent liquid forming the slurry. The slurry is washed to remove these materials by a process of continuous decantation, i.e., by continuously adding wash liquid, allowing the solid particles to settle, and removing a solid-free stream of wash liquid. As wash liquid there is added to the slurry recycled diluent, suitably in a proportion from about 75 to about 150% by volume, and preferably

about 120%, based on the slurry, and the mixture is transferred to a vessel wherein the urea particles continuously settle to the bottom and the wash liquid is taken off overhead. The particles of urea are collected at the bottom of the washer and pumped as a slurry to a second similar stage wherein the washing operation is repeated. A portion of the wash liquid leaving the first washer (e.g., about 60-70%) is combined with the wax-rich solution leaving the decomposer and is further processed together with the latter stream. The remaining wash liquid from the first washer is combined with the similar stream from the second washer and the combined stream is used to slurry the adduct cake from the filter. From the bottom of the second washer a slurry of regenerated and washed urea particles in diluent liquid is transferred to a pulp storage tank, wherein make-up quantities of diluent and urea are added as needed, and is then recycled to contact fresh charging stock.

My invention will be more fully understood from the following detailed description thereof in conjunction with the accompanying figure, which is a schematic flow diagram of a commercial plant for the production of low cold-test oils. Although my invention is applicable to the production of low cold-test oils having pour points ranging from about -10° F. to -70° F. from charging stocks having viscosities in the range from about 40 to 300 SSU at 100° F. and pour points within the range from about 0° to 100° F., it will be described with particular reference to urea-dewaxing of a distillate having a viscosity of about 80 SSU at 100° F., a pour point of about 0° F., and an adductable wax content of about 7% by weight. The charging stock 11, in an amount of about 1030 barrels per day, is combined with a slurry of recycled urea 12 in light alkylate (boiling range 120°-350° F.), said slurry comprising about 60 weight percent solid urea, in an amount of about 586 barrels per day and is passed through line 13 to cooler 14 wherein the temperature is lowered to about 80° F. To the combined oil and urea mixture there is added recycled diluent 15 comprising light alkylate in an amount of about 690 barrels per day (including approximately 2.7 barrels of make-up diluent), recycled methanol 16 in an amount of about 39 barrels per day (including about 1.2 barrels of make-up methanol), and water 17 as needed in an amount up to 10 volume percent based on the methanol. The combined mixture is passed through line 18 to reactor 19, which comprises a cylindrical vessel about 8 feet in diameter and 12 feet high, equipped with two "doughnut" baffles (e.g., 20) which divide the reactor into three mixing stages each equipped with a stirrer (e.g., 21). The heat of reaction liberated within the reactor causes the temperature of the mixture to rise to a maximum of about 90° F. The size of reactor 19 is such that the average residence time of the mixture therein is about one hour. With other feed stocks the flow rates may be adjusted so that an adduction time between about 0.1 and 1.5 hours or more is used.

From the reactor 19 the reaction products flow through line 22 to filter 23, which is a conventional continuous rotary drum filter with an effective area of about 150 square feet operated in an atmosphere of nitrogen under pressure supplied through line 24. The pressure of nitrogen may range suitably from 30 to 50 p.s.i.g. or higher as desired. Within the filter the rotating drum 25 forms a filter cake from the slurry 26 in which it is partially immersed. This filter cake is dislodged from the rotating drum by gas pressure and is directed by doctor blade 27 into the repulper 28. Prior to being dislodged the filter cake is washed on the filter drum to remove occluded oil with a stream of recycled light alkylate 29 entering through line 30, in an amount of about 690 barrels per day, and partially dried with a stream of nitrogen. Within the repulper 28 the adduct cake is reslurried with recycled light alkylate entering through line 31 by means

of stirrer 32, forming a slurry comprising about 1690 barrels per day having a solids content of about 30 weight percent.

The reslurried adduct is transferred through line 33 by means of slurry pump 34 and is heated by heater 35 to a temperature of about 220° F. in order to decompose the adduct. Other temperatures ranging up to about 240° F. and down to about 200° F. or below may also be used, although below 200° F. regeneration of urea becomes increasingly incomplete. Regeneration temperatures above about 240° F. are less desirable because excessive temperatures that exist locally in heater 35 tend to approach the melting point of urea and cause the decomposition of an increasingly large portion of the urea 15 passed through heater 35. The heated adduct stream is conveyed into decomposer 36 maintained at a pressure of about 20 p.s.i.g. and a temperature of about 220° F. This combination of pressure and temperature permits essentially all of the methanol contained within the entering stream to flash off together with a portion of the diluent. Removal of the methanol at this point prevents the readduction of the wax present in the diluent liquid with the urea as the temperature is lowered in subsequent stages of the operation. Obviously, other temperatures 20 and pressures can be used in the decomposer, provided that the temperature is sufficiently high to insure complete regeneration but not high enough to melt or decompose the urea, and that the pressure at the given temperature is low enough to permit substantially complete removal 25 of the methanol without flashing off excessive quantities of diluent. The vapors of methanol and diluent pass through line 37 to condenser 56, where they are condensed and passed to separator 57 in which diluent is separated from methanol and each is recycled for reuse, the diluent through line 58 and the methanol through line 59.

Within the decomposer 36 the liberated wax goes into solution in the diluent liquid and the urea is regenerated in the form of finely divided particles. An essentially solid-free solution of wax in diluent (about 1090 barrels per day) is taken off at a point near the top of decomposer 36 through line 38, while the particles of regenerated urea settle to the cone-shaped hopper 36a at the bottom of the decomposer 36 where they are collected and are pumped as a slurry containing about 60 weight percent solids by means of slurry pump 40 through lines 39 and 41 to washer 42. Also added to washer 42 is wash liquid consisting of recycled light alkylate supplied through line 43 in an amount of about 710 barrels per day. In washer 42 the urea particles again settle to the bottom and are conveyed as a slurry (about 60 weight percent solids) through line 44 to the second washer 45 to which is also added an additional 710 barrels per day of wash liquid (light alkylate) through line 46. The wax-containing wash liquid leaves washer 42 through line 47 in an amount of about 710 barrels per day and is split into two streams, a portion (about 450 barrels per day) going through line 48 to join a similar wax-rich diluent solution leaving the decomposer 36 through line 38. The remaining portion of the wash liquid from washer 42 joins through line 49 a similar stream leaving washer 45 through line 50. The combined stream is transferred via line 51 to the repulper 28 where it is used to reslurry the filter cake. The urea particles in the second washer 45 are collected at the bottom of the vessel and are transferred through line 52 to the pulp storage tank 53 to which make-up solid urea 53 and make-up diluent 54 are added as required to produce a urea slurry containing about 60 weight percent solids. The slurry is recycled via line 55 to contact fresh charging stock.

The filtrate leaving filter 23 through line 60, comprising dewaxed oil, diluent, and a portion of the methanol, passes to filtrate accumulator 61 where the inert gas (nitrogen) is separated through line 62 and is recompressed by compressor 63 for reuse. Make-up nitrogen is added through line 64 as needed. The diluted oil

(about 2320 barrels per day) leaves accumulator 61 via line 65 and pump 66, is heated by means of heater 67 to a temperature of about 200° F. and enters flash drum 68 wherein essentially all the methanol and a portion of the diluent flash off, are passed through line 69 and condenser 56 into separator 57 where these materials are separated and recycled. The diluted oil, stripped of its methanol content, leaves the flash drum through line 70 and pump 71 into the stripper 72, which is operated at a pressure of about 3-10 p.s.i.g. and a temperature of about 230° F. at the top and 380° F. at the bottom with open steam 73 being supplied at the bottom through line 74. Steam and diluent vapors leave stripper 72 through line 75 to condenser 76 and separator 77 wherein the water is separated and discarded through line 78 and a portion (about 520 barrels per day) of the condensed diluent is returned as reflux to stripper 72 through line 79 and valve 80. The stripped low pour oil leaves the stripper through line 81 to a suitable dehydrator (optional, and not shown) and then to storage. The low cold-test product, amounting to about 910 barrels per day, has a pour point of about -45° F. Operating in a similar manner, the plant is capable of producing about 750 barrels per day of -50° F. pour oil from a charging stock having a viscosity of about 50 SSU (100° F.) and an initial pour point of about 0° F., and about 1120 barrels per day of a -25° F. pour oil from a charging stock having a viscosity of about 220 SSU (100° F.) and an initial pour point of about 0° F.

The combined wax-rich diluent streams leaving de-composer 36 and washer 42 through lines 38 and 48 respectively pass via line 82 and pump 83 to heater 84 wherein the stream is heated to about 350° F. and introduced to wax flash tower 85. Most of the diluent flashes off through line 86 and the remaining concentrated solution of wax in diluent leaves tower 85 through line 87 and pump 88 to heater 89, wherein it is heated to about 400° F., and enters wax stripper 90 to which is supplied open steam through line 91. Steam and diluent vapors leave stripper 90 through line 92, are combined with diluent vapors in line 86 leaving wax flash tower 85, and are passed through line 93 and condenser 76 to separator 77. A portion of the separated diluent is returned as reflux to wax flash tower 85 (about 390 barrels per day) through lines 94 and 95 and to wax stripper 90 (about 5 barrels per day) through line 96. The remaining diluent leaves separator 77 through line 97 and is recycled to the contacting stage. Stripped wax product (about 120 barrels per day) leaves wax stripper 90 through line 98 to storage.

While I have described in detail specific examples of my invention, it should be understood that various alternative operating procedures and operating conditions will be apparent to those skilled in the art.

I claim:

1. A continuous process for dewaxing a wax-containing hydrocarbon oil having a viscosity in the range of about 40 to about 300 SSU at 100° F., which process comprises adding to said oil solid urea in an amount of at least about three pounds per pound of wax in the oil, about 0.5% to about 10% by volume, based on the waxy oil, of methanol, and about 0.1 to about 3 volumes of an inert hydrocarbon diluent liquid per volume of said oil, contacting the resulting mixture at about 40° to about 120° F. for a time to effect adduct formation, separating adduct and unreacted urea from diluted oil, separating methanol and diluent from the oil to obtain a product of low pour point, repulping the separated adduct and unreacted urea with wax-containing diluent liquid from a subsequent washing zone and pumping the repulped material to a decomposing zone which is at a temperature above about 180° F. but below the melting point of urea, removing methanol vapor from the decomposing zone and condensing the vapor for reuse, separating a solution of liberated wax in diluent liquid from

regenerated solid urea, stripping the wax solution to remove diluent liquid therefrom, washing the regenerated solid urea with diluent liquid, recycling wax-containing wash liquid to said repulping step, slurring the washed regenerated solid urea with diluent liquid and recycling the resulting slurry to the contacting step, and returning to the contacting step methanol and diluent liquid separated from the diluted oil, from the wax solution, and from the decomposing step.

2. A continuous process for treating a wax-containing Mid-Continent oil having a viscosity in the range of about 40 to about 300 SSU at 100° F. and a pour point in the range of about 0° to about 100° F., and obtaining therefrom a low cold-test oil having a pour point in the range of about -10° F. to about -70° F., which process comprises adding to said oil solid finely-divided urea in an amount of about 4 to 6 pounds per pound of wax in the oil, about 0.5% to about 10% by volume, based on the waxy oil, of methanol, and about 0.5 to about 1.5 volumes per volume of said oil of an inert hydrocarbon diluent comprising a liquid alkylate fraction boiling between about 120° F. and 350° F., contacting the resulting mixture at about 80° F. to about 100° F. for about 0.1 to about 1.5 hours to effect adduct formation, separating adduct and unreacted urea from diluted oil, separating methanol and diluent from the oil to obtain the desired low cold-test product, repulping the separated adduct and unreacted urea with wax-containing liquid from a subsequent washing zone to obtain a slurry and pumping the resulting slurry to a decomposing zone which is at a temperature between about 200° F. and about 240° F., removing methanol vapor from the decomposing zone and condensing the vapor for reuse, separating a solution of liberated wax in diluent liquid from regenerated solid urea, stripping the wax solution to remove diluent liquid therefrom, washing the regenerated solid urea with diluent liquid by continuous decantation, recycling wax-containing wash liquid to said repulping step, slurring the washed regenerated solid urea with diluent liquid and recycling the resulting slurry to the contacting step, and returning to the contacting step methanol and diluent liquid separated from the diluted oil, from the wax solution, and from the decomposing step.

3. A continuous process for dewaxing a wax-containing Mid-Continent oil having a viscosity in the range of about 40 to 300 SSU at 100° F. and a pour point of about 0° F. to about 10° F. and obtaining therefrom a low cold-test oil having a pour point of about -10° F. to about -70° F., which process comprises adding to said oil solid urea in an amount of about 4 pounds per pound of wax in the oil, about 3% by volume, based on the waxy oil, of methanol, and about 1 volume per volume of said oil of an inert hydrocarbon diluent comprising a liquid alkylate fraction having a boiling range of about 120° F. to about 350° F., contacting the resulting mixture at about 90° F. for about one hour to effect adduct formation, filtering adduct and unreacted urea from diluted oil, separating methanol and diluent from the oil to obtain the desired low cold-test product, repulping the separated adduct and unreacted urea with sufficient wax-containing diluent liquid from a subsequent washing zone to obtain a slurry having a solids content of about 30 weight percent, pumping the repulped material to a decomposing zone which is at a temperature of about 220° F. and a pressure of about 20 p.s.i.g., flashing methanol vapor from the decomposing zone and condensing the vapor for reuse, allowing the heated repulped material to settle and separating therefrom a solid-free solution of liberated wax in diluent liquid and a slurry of regenerated solid urea having a solids content of about 60 weight percent, stripping the wax solution to remove diluent therefrom, washing the slurry by adding thereto a wash liquid comprising said diluent liquid in an amount of about 1.2 volumes per volume of slurry, stratifying and separating said mixture to obtain solid-free wax-contain-

ing wash liquid and a slurry of urea having a solids content of about 60 weight percent, repeating said washing operation, recycling wax-containing wash liquid to said repulping step, recycling the slurry of washed regenerated solid urea to the contacting step and returning to the contacting step methanol and diluent liquid separated from the diluted oil, from the wax solution, and from the decomposing step.
